(57) **CLAIM**

The ornamental design for a fastener with integral spring clip, as shown and described.

DESCRIPTION

FIG. 1 is a bottom perspective view of our fastener with integral spring clip showing our new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a left end view thereof, the right end being a mirror image thereof.
